FURNACE FOR BURNING POWDERED FUEL

Filed July 3, 1922

Patented Mar. 31, 1925.

UNITED STATES PATENT OFFICE.

MILTON KRAEMER, OF NEW YORK, N. Y., ASSIGNOR OF ONE-HALF TO EDWARD A. GEOGHEGAN, OF NEW YORK, N. Y.

FURNACE FOR BURNING POWDERED FUEL.

Application filed July 3, 1922. Serial No. 572,692.

To all whom it may concern:

Be it known that I, MILTON KRAEMER, a citizen of the United States, residing at New York, in the county of New York and State of New York, have invented certain new and useful Improvements in Furnaces for Burning Powdered Fuel; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to furnaces for burning powdered fuel, and particularly to such furnaces for steam generators.

The object of this invention is to provide for the introduction of sufficient heated air into the semicylindrical furnace chamber to produce complete combustion of the powdered fuel in the furnace chamber.

The features of my invention are herein-after described and pointed out, and are illustrated in the accompanying drawings in which:—

Figure 1, is a vertical section of a vertical water tube boiler setting showing my invention installed therein.

Figure 2, is a like view of a furnace chamber constructed according to my invention for a horizontal water-tube boiler.

Figure 3 is a plan view of one of the draft controlling slides.

In these drawings A is the base of the setting; A' is the vertical fire wall at the rear of the semicylindrical furnace chamber B, having in the base thereof a transverse air draft duct a, from which vertical slots or ducts a' lead upwardly through the fire wall to the upper end thereof. The front surface of the fire wall A' is preferably curved as shown at a'', so as to throw the flames forwardly at the upper part of the chamber B. I also preferably make an opening a''' in the front of the fire wall A' from the duct a'.

In Fig. 1, the furnace chamber B is provided with an upper inclined wall C, and projecting from the under side of the upper inclined wall C is a deflecting wall C' which extends into the furnace chamber B sufficiently to cause the flames to impinge against the curved front surface a'' of the

fire wall A'. The deflecting wall C' is provided with an air duct c which extends downwardly in said wall from the upper surface of the cover C and preferably turns and opens through the rear side of the deflector C'.

I also preferably provide an auxiliary air draft slot or opening c' in the inclined upper wall C in front of the deflector C' to supply air when needed. D indicates a powdered fuel feeding apparatus of ordinary construction, from which a spout d extends through the inclined upper wall C into the semicylindrical furnace chamber B in front of the deflector C', the exit end d' of the spout d being bent sufficiently to throw the fuel toward the fire wall A. I also preferably provide a series of air draft jets E through the furnace wall, having the exit ends thereof adjacent to the exit ends d' of the fuel spout d. I preferably provide each of the air supplying slots or ducts c, c' and E with controlling slides or valves, F, F', and F'', so that the air drafts can be regulated as desired.

In Fig. 2 my invention is shown adapted for use in association with a horizontal water tube boiler. In this figure the fire wall A'' at the rear of the semicylindrical furnace chamber B', is provided with a curved front surface a''. A transverse air chamber a''' is located near the base thereof from which an air duct a'' extends upwardly and opens through the top of said wall so that air travelling upwardly therethrough becomes heated before it enters the combustion chamber. From the duct a'' there is a branch opening a'' through the front surface of the fire wall into the furnace chamber B'. C'' indicates a vertical front wall of the furnace chamber, and projecting inwardly from said wall is a deflector wall C'', through which there is an air passage c'', through which air may flow and become heated before it is discharged therefrom into the combustion chamber.

D' indicates a fuel feeding apparatus from which a fuel duct leads into the lower portion of the furnace chamber B', the inner or exit end d'' thereof being curved upward to direct the fuel upwardly. E' indicates an air supply duct adapted to supply an upwardly directed current of air adjacent to the exit end of the fuel duct d'', f and F'' indicates slidable valve mechanisms adapted

to control the volume of air admitted to the air passage c^2 and c^3 .

In operation the flames produced by the burning of powdered fuel injected into the chamber B or B' through the nozzle d' or d^3 are projected toward the curved front face a^2 or a^3 of the fire wall A' or A³ which heats the same so that the air flowing through the draft duct a' or a^4 becomes heated before it is delivered from the upper end thereof; likewise the flames cause the deflecting wall C' or C³ to become heated, thereby causing the air flowing through the draft duct c or c^2 to become heated before its delivery into the chamber B or B'. Air flowing into the chamber B or B' through air jet E or E' is delivered adjacent to the end of the nozzle d' or d^3 of the spout d or d^2 so that the flames from the nozzle is projected toward the deflector C' or C³ and fire walls A' or A³.

The air is drawn through the several air ducts by means of the ordinary draft from the stack (not shown). The auxiliary air supply ducts c' or c^3 is used principally during the peak loads to enhance the combustion in that portion of the chambers B or B' around the nozzle d or d^3 and prevent the accumulation of cinders thereabout.

Having thus fully described my invention so that the same can be utilized by others, I do not desire to confine myself to the exact form or construction shown and described, as many modifications can be made therein without departing from the scope of my invention; therefore what I claim as new and desire to secure by Letters Patent is:—

1. In an apparatus of the class described, a semi cylindrical combustion chamber with the axis thereof transverse of the furnace structure said chamber extending from side wall to side wall of the structure and having an opening therefrom to the boiler space parallel with said axis, a wall projecting into said chamber to a point adjacent to said axis, means to supply fuel to said chamber below said wall, and means to admit air to said opening.

2. In an apparatus of the class described, a semi-cylindrical combustion chamber having its axis transverse to the furnace structure, the rear wall of said chamber having an air passage therein adjacent to, and adapted to discharge air through the front surface thereof, said chamber having an opening therefrom to the boiler space parallel with the axis of said chamber, an inclined wall above the axis of said chamber and forming the roof thereof, a deflecting wall extending from said inclined wall into said chamber to a point adjacent to said axis and having an air passage therein to discharge air into said opening, and means to supply fuel to said chamber below said deflector and in front of said axis. 65

3. In an apparatus of the class described, a semi-cylindrical chamber having the axis thereof transverse of the furnace structure and having an opening therefrom to the boiler space parallel with said axis, said chamber extending from side wall to side wall of the structure, a radial deflector wall projecting into said chamber to a point adjacent to said axis and having an air inlet passage therethrough adapted to discharge heated air into the opening from said chamber, and means to supply fuel to said chamber below said deflector wall. 70

4. In an apparatus of the class described, a chamber extending from side wall to side wall and having a rear wall provided with a semi-cylindrical curved front surface with the axis thereof transverse to the furnace structure and having an air passage therein adjacent to said front surface, and adapted to discharge heated air into said chamber, a deflector wall projecting into said chamber to a point adjacent to the axis thereof whereby the products of combustion will be deflected toward said rear wall, and means to supply fuel to said chamber under said deflecting wall. 75 80 85 90 95

In testimony whereof I affix my signature.

MILTON KRAEMER.
